UNITED STATES PATENT OFFICE.

ARTHUR J. RAY AND HARLEY B. McELYEA, OF CHICAGO, ILLINOIS, ASSIGNORS, BY
MESNE ASSIGNMENTS, TO AUTOMATIC ELECTRIC INC., OF CHICAGO, ILLINOIS, A
CORPORATION OF DELAWARE.

AUTOMATIC TELEPHONE SYSTEM.

Application filed February 19, 1921, Serial No. 446,319. Renewed May 11, 1925.

This invention relates in general to automatic telephone systems, but more particularly to such systems as comprise a number of more or less widely scattered automatic exchanges which may be of various sizes and classes and which are interconnected by toll or long distance lines, and the object of the invention in general is to provide new and improved circuit arrangements whereby a toll operator may establish connections between the various subscribers of the different exchanges, and whereby she can supervise the calls and make proper charges for the same while using a minimum of equipment.

Considered more in detail, an important feature of the invention consists in the provision of improved circuits whereby the toll operator may call a subscriber over a trunk line and then call a second subscriber over the same trunk line and whereby she is given complete supervision by each subscriber separately.

A further feature relates to toll or way stations which may be located at intermediate points on toll lines connecting two automatic exchanges. Novel circuit arrangements are shown providing for automatic calling to and from a station of this kind.

The foregoing and other improvements will be described fully hereinafter, reference being had to the accompanying drawings.

Although as stated there may be several automatic exchanges of different sizes and variety in a system of this kind, it has been decided to illustrate the invention in connection with a system which includes a large automatic exchange at which there is a toll operator and two small community automatic exchanges, or C. A. Xes as they are

abbreviated, neither of which has an operator, that are so located that one is much nearer to the large exchange than the other and lies between the two since this arrangement affords an opportunity to describe the various features to good advantage. In the drawings, comprising Figs. 1-6, inclusive, there is shown by means of the usual circuit diagrams sufficient of the apparatus in the above mentioned hypothetical system to enable the invention to be explained and understood.

Referring to Fig. 1, the apparatus shown

at the left of the sheet is located in the large automatic exchange and includes the equipment individual to a single trunk line, of which there may be several between the automatic exchange in which the operator is located and the nearer community automatic exchange. The ring down drop 143 is provided for the purpose of signalling the operator when a subscriber obtains connection with the toll trunk line 131-132 at the distant end. The jacks J and J' are provided for the purpose of answering calls and for calling out over the trunk line shown. The keys K and K² are arranged to connect the calling device S' in the associated control circuits at the proper times, as will be subsequently explained. The key K' is a release key and may be used in releasing a connection while the calling device S' is in the circuit. The jack J² is provided for the sole purpose of calling the intermediate substation Q, Fig. 4, and is similar to jacks J and J' with the exception that the usual supervisory relay such as supervisory relay 140 associated with jack J' is replaced by resistance R⁶.

The equipment on the right of toll trunk line 131-132, is in the nearer C. A. X. The relay group E momentarily projects generator out on toll line 131-132 to operate drop 143 when the toll line is called, and also provides a holding circuit for whatever switch seizes it. The switching apparatus shown in Figs. 2, 3, and 4, is also in the nearer C. A. X. while the switching apparatus shown in Figs. 5 and 6 is located in the farther C. A. X., and the substation Q (Fig. 4) is a toll substation located on the toll line between the two C. A. Xes.

The telephone substations with the exception of the substation Q are of the usual automatic type. The substation A, for example, comprises the usual transmitter, receiver, and ringer, and the calling device S for controlling the automatic switches. The substation Q consists of the usual transmitter, receiver, and ringer and also has a local battery and an induction coil in accordance with the usual practice when common battery cannot be supplied. The key K³ is provided for the purpose of switching the circuit to the proper condition for answering a call or making one as the case may be.

The battery X is approximately the same potential as the exchange battery and is preferably composed of dry cells.

The individual line switches, such as the line switches C and C' Figs. 2 and 6, which are associated with the lines of substations A and A', respectively, are of the well known rotary type, in which the wipers have no normal position and move in a forward direction only. These line switches are in common use and their construction and function is well understood.

The selectors D, D', D², and D³, Figs. 2, 3, and 5, are of the usual Strowger vertical and rotary type having their bank contacts arranged in horizontal rows or levels, and are operated according to the well known two wire system of control. The circuits are shown complete in the drawings and will be described hereinafter.

The connectors H and H', Figs. 2 and 6, are mechanically the same as the selectors D, D', D², and D³. The circuit shown for connector H, and likewise for connector H' is a simple two wire circuit which is in common use.

The selector repeaters G and G', Figs. 4 and 5, which are associated with the two opposite ends of the toll line connecting the two community automatic exchanges, are also of the same mechanical construction as the selectors D, D', D², and D³, having special relays and circuits added, however, that enables either of them to function as an ordinary repeater when seized locally, while either acts as a selector in response to the first digit and thereafter as a repeater when operated from the toll line.

The repeater F, Fig. 3, is operated over one conductor of the toll line 131-132, while the repeater F' is operated over the other. The function of each is to translate grounded impulses into two wire impulses and repeat them to its associated selector D' or D² as the case may be.

The relay group P, Fig. 4, is provided for the purpose of signalling the toll station Q which, as before stated, is located on a toll line between the two C. A. Xes. Access to the relay group P is obtained by the operator by calling a different digit than the one ordinarily called when it is desired to operate the switch G' on the distant end of the toll line.

The apparatus having been described more or less in general will now be described in connection with a detailed description of its operation.

In general a call from one C. A. X. to another or to the toll station Q is completed as follows: When a subscriber in one C. A. X. wishes to obtain connection with a subscriber in the other C. A. X. he calls the operator by dialling 0 or 00, depending upon whether his line terminates in the nearer or

further C. A. X. The operator answers and ascertains the number of the calling subscriber and also the number of the subscriber desired. She then instructs the calling subscriber to hang up his receiver and when he does so he releases the connection. Then she calls his number to make sure that he has given his own number and not another. When he answers she tells him to wait on the line while she dials the subscriber wanted. When the called subscriber answers he can obviously converse with the calling subscriber while the operator may converse with either or both, and all through the connection she maintains damp supervision over both the calling and the called subscribers except when one of them is the subscriber at substation Q.

It will now be assumed that the subscriber at substation A desires to obtain connection with the subscriber at the toll station Q, which is located on the toll line between the two C. A. Xes. The number of substation A is assumed to be 123 while the number at substation Q is assumed to be 3.

When the receiver is removed at the calling substation A a circuit is completed over the conductors 11 and 13 for the line relay 15 of the line switch C. Upon energizing, relay 15 closes a circuit at armature 18 which includes the winding of the switching relay 14 and the stepping magnet 16 in series; and at armature 17 connects test wiper 23 to the above circuit at a point between the switching relay 14 and the stepping magnet 16. The operation now depends upon whether the trunk line with which the line switch wipers are associated is busy or idle. If the trunk line is busy there is a ground potential upon the test contact with which the test wiper 23 is in engagement; the switching relay 14 is short circuited and the stepping magnet 16, which interrupts its own circuit, operates in the manner of a buzzer to advance the switch wipers in search of an idle trunk line. However, we may assume in the present case that when the call is initiated the trunk line upon which the wipers of the line switch are standing is idle. Under these circumstances when the line relay 15 is energized the switching relay 14 is not short circuited and the stepping magnet 16 is not operated because of the high resistance of relay 14. The latter relay, however, is energized, grounds the test wiper 23 at armature 20, and at armatures 19 and 21 disconnects the line conductors 11 and 13 from the winding of line relay 15 and from ground, respectively, and extends them by way of wipers 22 and 24, bank contacts 25 and 27, trunk conductors 28 and 30, and armatures 49 and 52 and their resting contacts to the upper and lower windings, respectively, of line relay 35 of the selector D. The line and release relays 35

and 36 of selector D energize immediately and the latter grounds the release trunk conductor 29 before the slow acting line relay 15 of the line switch C has time to deenergize, thereby establishing a holding circuit for switching relay 14 of line switch C as follows: from ground through the working contact of armature 41 and said armature of release relay 36, release trunk conductor 29, test contact 26, test wiper 23, armature 20 and its working contact, switching relay 14, and stepping magnet 16 to battery. By means of this ground potential on the multiples of test contact 26 the selector D is rendered busy to the other line switches having access to it; and a branch of this holding circuit extends by way of private normal conductor 12, to test contact 95 and its multiples in the banks of the connectors having access to the line of substation A, thereby protecting it against intrusion in the usual manner.

The subscriber at substation A may now operate his calling device in accordance with the digit 0, which is the call number of the toll recording operator located in the large automatic exchange, and when he does so the line relay 35 of selector D is deenergized ten times momentarily. Each time the line relay 35 of selector D is deenergized due to the opening of its circuit at the calling device S of the calling substation A, a circuit is closed at armature 40 for the vertical magnet 56 in series with the slow acting relay 37 as follows: from ground through the resting contact of armature 51 and the said armature, armature 40 and its resting contact, armature 42 and its working contact, relay 37, and vertical magnet 56 to battery. By the operation of the vertical magnet the switch shaft and wipers are raised step by step until the wipers stand opposite the tenth level of bank contacts. Relay 37 energizes and retains its armature attracted throughout the vertical movement of the shaft, and upon the closure of the vertical off normal springs 44 completes a circuit for the stepping relay 38. Upon energizing, relay 38 prepares the circuit of the rotary magnet 58 at armature 47, and at armature 46 establishes a locking circuit for itself. At the end of the vertical movement the slow acting relay 37 deenergizes and completes a circuit for the rotary magnet 58 which thereupon energizes to advance the wipers 53—55, inclusive, into engagement with the first set of bank contacts in the level opposite which they are raised. The rotary magnet also breaks the circuit of the stepping relay 38 at interrupter contacts 48. The stepping relay 38 immediately deenergizes and breaks the circuit of the rotary magnet which thereupon deenergizes also and again closes the interrupter contacts. The operation now depends upon whether the test contact with which the test wiper 54

is in engagement is busy or idle. If the test contact is busy it has a ground potential on it and the stepping relay energizes again and the same cycle of operation is repeated over and over until an idle or ungrounded test contact is reached. When an idle set of contacts is reached the switching relay 39 energizes in series with the stepping relay 38 over the following circuit: from grounded release trunk conductor 29, through switching relay 39, interrupter contacts 48 of rotary magnet 58, vertical off normal springs 44, and stepping relay 38 to battery. Relay 38, however, due to its relatively small number of turns does not energize over this circuit. It is assumed that test contact 57 is the first one found idle. In this case the energization of relay 39 switches the connection through to the trunk line terminating in contacts 56 and 58, and comprising conductors 106 and 108. These conductors lead to and terminate in the line relay 120 of relay group E. As soon as the switching relay 39 operates it connects ground to test contact 57 by way of armature 50 in order to make the seized trunk busy immediately. In addition to making the seized trunk busy this ground extends by way of conductor 107, armature 282 and its resting contact, armature 209 and its resting contact, conductor 109, armature 126 and its resting contact, and slow acting relay 122 to battery. Slow acting relay 122, upon energizing, closes at armature 129 a circuit for slow acting relay 123. Upon energizing, relay 123 projects ringing current by way of armatures 129 and 130 onto the trunk line comprising conductors 131 and 132. This induces an alternating current in the secondary winding of repeating coil T, thereby operating the drop 143 in front of the operator in the large automatic exchange. However, at the same time that the circuit is closed for slow acting relay 122 the extending of the connection closes a circuit for line relay 120 as has been previously explained. The two relays 120 and 122 are operated practically simultaneously. When line relay 120 operates it closes a circuit at armature 124 for release relay 121 which energizes and opens the circuit of the slow acting relay 122 thus allowing it to deenergize and open the circuit of slow acting relay 123 which later falls back and removes generator from toll line 131—132. Due to the combined slowness of relays 122 and 123 the drop 143 in front of the operator is operated before generator is removed. Relay 121 in addition to opening the circuit of relay 122, grounds release trunk conductor 109 thereby completing a holding circuit that extends back by way of conductor 107 to selector D to hold it and line switch C in their respective operated positions. It is understood that this circuit is established before the slow acting release relay 36 of selector D has time to de-

- energize. The operator upon seeing the operated condition of the drop 143 restores it to normal and inserts a plug (not shown) of an idle cord circuit into the jack J and in 8 any well known or preferred manner associates her head set (not shown) with the cord circuit just taken for use. She may now converse with the calling subscriber in the usual manner and after being informed 14 as to the subscriber desired and the number of the calling subscriber she instructs him to hang up his receiver and when he does so line relay 120 deenergizes with the result that release relay 121 deenergizes also and 15 removes ground from release trunk conductor 109, thereby allowing the switch C to assume normal circuit conditions and also allowing switch D to release.
- The operator may be engaged with other 20 duties and consequently not have time to listen for a click or other noise to inform her that the calling subscriber has hung up. In this case she need only observe the lamp 147 at intervals for when the release 25 relay 121 of relay group E deenergizes it closes a circuit at armature 125 and its resting contact for supervisory relay 139 which operates armature 142 to close an illuminating circuit for lamp 147. The energizing 30 circuit for supervisory relay 139 is as follows: from ground through line relay 204 of repeater F, resting contact of armature 212 and said armature, control conductor 163, upper winding 161 of double wound 35 impedance coil I', resting contact of armature 125 and said armature, resting contact of armature 129 and said armature, trunk conductor 131, upper winding 134 of double wound impedance coil I, spring 145 of jack 40 J and its working contact, normally closed springs controlled by spring 137 of key K, and supervisory relay 139 to battery. In addition to relay 139 line relay 204 of repeater F operates over the above traced circuit and at armature 216 closes a circuit for slow acting release relay 200. Release relay 200, upon energizing, extends ground to release trunk conductor 107 by way of the working contact of armature 209 and said 45 armature, and resting contact of armature 282 and said armature. This ground on release trunk conductor 107 guards the toll line 131-132 against intrusion at the automatic end thereof by preventing the seizure 50 of said line by way of the relay group E. Relay 200, upon energizing, in addition to grounding the release trunk conductor as described also closes at armature 208 a circuit for the upper or polarizing winding of 55 electro polarized relay 202. This winding consists of few turns of high resistance wire and consequently cannot operate relay 202 until it is assisted to by current in the lower winding. Returning now to the line 60 relay 204, that relay, upon energizing, not

only closes the circuit for relay 200 at armature 216 as above described, but also closes at armature 217 a bridge across conductors 225 and 226 including the impedance 71 206, and the lower winding of polarized relay 202. When this bridge is closed the line relay 227 of selector D' energizes and closes the circuit for release relay 228, thus preparing the switch for operation in the usual manner. The electro-polarized relay 202 76 does not energize at this time because the current flowing in its lower winding opposes that flowing in its upper winding.

The operator upon seeing the lighted condition of lamp 147, as before described, 80 knows that the calling subscriber has hung up, thereby leaving the trunk free for her to proceed with the call, and she throws key K in the proper direction thereby operating spring 137 which removes relay 139 85 from the circuit, thereby extinguishing lamp 147, and inserts the calling device S' in its place, the calling device S' being connected to battery through the low protecting resistance R. The operator may now operate 90 the calling device S' in accordance with the first digit 1 of the number of substation A, assumed to be 123. When the calling device S' is operated in accordance with the first 95 digit 1 of the desired number, line relay 204 of repeater F is deenergized once momentarily. When the line relay 204 is deenergized, it closes a circuit extending from ground by way of armatures 216, 214, and 207 to slow acting relay 201. Relay 201 100 operates and closes at armature 210 the bridge across conductors 225 and 226 by a more direct path excluding relays 202 and 206. When there are several impulses to be transmitted, the slow acting relay 201 remains 105 energized throughout and obviously deenergizes again upon their cessation. This is the usual expedient made use of to obtain first class switch control. At this time, however, there is but one impulse to be transmitted and when line relay 204 deenergizes, as previously described, it repeats at armature 217 the impulse to the line relay 227 of selector D' which steps its wipers up 110 to the first level and rotates them in search of an idle trunk line. It will be understood that since the circuit of selector D' is identical with the circuit of switch D that the operation of the former need not be explained as the operation of switch D has already 115 been explained fully. Assuming that the trunk line terminating in bank contacts 249-251, inclusive, is the first one found idle, the energization of switching relay 221 extends the connections by way of armatures 120 233 and 236 and their working contacts, wipers 240 and 242, bank contacts 249 and 251, trunk conductors 258 and 260, and normally closed contacts of reversing relay 67 of connector H to the upper and lower wind- 130

ings of the double wound line relay 66. When the line is thus extended the line and release relays 66 and 65, respectively, of connector H energize and the latter prepares the switch for the vertical operation and grounds the release trunk conductor 259 in order to guard the trunk against intrusion and also to hold the selector D' in its operated position.

- 10 The operator may now operate her calling device S' for the second digit of the desired number. As a result the line relay 204 of repeater F is deenergized twice momentarily and repeats the impulses to the line relay 66 of connector H which is also twice deenergized. Each time the line relay 66 deenergizes armature 88 sends an impulse of current to the vertical magnet 69 in series with the slow acting relay 64 by way of the following circuit: from ground through armature 88 and its resting contact, armature 85 and its working contact, off normal spring 98, off normal spring 87, relay 64, and vertical magnet 69 to battery. By the operation of the vertical magnet the wipers 91-93, inclusive, are raised step by step until they stand opposite the second level of bank contacts. It is in this level that the line of substation A terminates. The slow acting series relay 64 is energized in series with the vertical magnet and by means of its armature 84 maintains the circuit of the vertical magnet intact after the operation of the off normal springs, which occurs at the end of the first vertical step. At the end of the vertical movement the slow acting relay 64 deenergizes and transfers the operating circuit to the rotary magnet 68.

15 The operator will now operate her calling device in accordance with the last digit 3 of the called number. When the calling device is operated the line relay 66 responds to the impulses repeated to it as before and sends three impulses to the rotary magnet 68 over the following circuit: from ground by way of previously traced circuit to spring 98 and thence by way of spring 97, armature 84 and its resting contact, resting contact of armature 77 and said armature, armature 74 and its resting contact, and rotary magnet 68 to battery. By the operation of the rotary magnet the wipers 91-93, inclusive, are rotated step by step until they come to rest on the third set of contacts in the level opposite which they were raised. These bank contacts are indicated in the drawing by the numerals 94-96, inclusive, and are the bank contacts in which the line of substation A terminates. The slow acting relay 61 is energized in multiple with the rotary magnet and retains its armatures attracted throughout the rotary movement. At armature 75, relay 61 connects test relay 62 with test wiper 92, and at armature 76 the said relay 61 closes a shunt around armature 77

of test relay 62 and its resting contact. The latter operation is to prevent the test relay from opening the rotary magnet circuit while the test wiper is passing over busy test contacts.

20 It will be assumed first that for some reason the line of substation A has become busy since the subscriber thereat hung up after calling the operator, as previously explained. Such being the case, when the test wiper 92 arrives at test contact 95 there is a ground potential thereon, the busy test relay 62 is energized, and when the slow acting relay 61 deenergizes at the end of the rotary movement a locking circuit is established for the test relay 62 as follows: from grounded release trunk conductor 259 through armature 78 and its working contact, normally closed contacts operated by armature 75, and test relay 62 to battery. Relay 62 opens the rotary magnet circuit at armature 77, in order to prevent further movement of the wipers if the calling device should be turned again, and at armature 79 connects a lead from the busy signalling machine B to the lower heavy talking conductor. By this operation an audible signal is transmitted to the calling operator and, being advised thereby that the called line is inaccessible for the time being, she will operate key K', Fig. 1, and thereby release the connection.

25 In the present case, however, we may assume that the line of substation A is idle when called. In that case when the test wiper 92 arrives at test contact 95 the latter is not grounded and the test relay 62 is not energized. When the slow acting relay 61 deenergizes at the end of the rotary movement it completes at armature 75 a circuit for the switching relay 60 as follows: from grounded release trunk conductor 259 by way of armature 78 and its resting contact, upper winding of switching relay 60, resting contact of armature 75 and said armature, test wiper 92, test contact 95, normal conductor 12, switching relay 14 of line switch C, and stepping magnet 16 to battery. Switching relays 60 and 14 are operated in series over this circuit, and the latter clears the called line of its normal battery and ground connections in the line switch C. It may be stated here that due to an interlocking device (not shown) between the armatures of line relay 15 and the armatures of switching relay 14 that the armatures of relay 14 are operated only about half way and consequently the wipers are not connected up at this time. In the connector H, when the switching relay 60 energizes, it establishes a locking circuit for itself at armature 73, grounds the test wiper 92 at armature 72, opens the circuit of the rotary magnet at armature 74, and at armatures 71 and 99 completes the connection to the line wipers 91 and 92.

The connection has now been completed to the desired called line and ringing current is intermittently projected out over the line conductors 11 and 13 to operate the 5 bridged ringer at substation A. The ringing circuit is of the usual character and need not be described in detail. When the called subscriber responds by removing his receiver from the hook, the ring cut off relay 10 63, the upper winding of which is included in the return circuit of the generator, operates and at armature 81 locks itself to grounded release trunk conductor 259. Relay 63 also breaks the ringing circuit at the 15 resting contacts of armatures 80 and 82 and at the working contacts of these same armatures completes the talking circuit. The transmitter at substation A is now supplied with talking current through the windings 20 of the double wound back bridge relay 67, and this relay is accordingly energized with the result that the incoming conductors 258 and 260 are reversed as regards their connection with the windings of the line relay 66. 25 It follows that the direction of current flow in the trunk line and the bridge at repeater F is reversed. The two windings of the electro polarized relay 202 of repeater F, which heretofore have opposed each other 30 now assist each other in operating the said relay. Upon energizing, relay 202 closes at armature 211 the circuit of slow acting relay 203. Relay 203, upon energizing, closes a shunt at armature 215 and its working contact around armature 217 and its working contact, closes a multiple point in the circuit of release relay 200 at armature 213, opens the circuit of relay 201, and at armature 212 transfers the operator's control circuit conductor 163 from the line relay 204 to relay 205. Line relay 204 immediately deenergizes but owing to the operation of relay 203, as previously explained, it does not have any effect. 40 The control circuit has now been switched from the grounded to the ungrounded pole of battery at the repeater F and the effect of this operation at the distant exchange will now be considered. Assuming that the 45 operator restores her key K to normal while waiting for the called subscriber to answer, which will ordinarily be the case, the supervisory relay 139 operates and lights the supervisory lamp 147. Now when the other 50 end of the control circuit is switched from ground to battery no current flows over the said circuit and consequently the supervisory relay 139 deenergizes and extinguishes lamp 147. The operator, upon seeing lamp 147 become extinguished, knows that the called party has answered and she immediately associates her head set with the 55 cord circuit in use. 60 The operator may now converse with the 65 called subscriber and upon ascertaining that

he is the one that desires the connection tells him to wait on the line while she calls the desired subscriber, being in this case the one at substation Q. The operator now inserts the other plug belonging to the cord circuit 70 in use into jack J², that being the proper jack to use when calling substation Q. It is easily seen that as soon as a plug is inserted into the jack J² that the line relay 275 and the release relay 276 of repeater F' 75 operate in the same manner as the line and release relays of the repeater F operated in the previous example, battery being fed out through resistance R⁸ and spring 170, and since the two repeaters are identical the result in this case as in the previous one is that the line relay closes a bridge across the trunk conductors 283 and 284 of the associated selector, which in this case is the selector D², while the energization of the release relay makes the repeater ready to repeat impulses. Obviously, the closing of the bridge across the trunk conductors 283 and 284 energizes the line and release relays 285 and 286 of the selector D² and makes the 80 switch ready to operate. 85

The energizing circuit of the line relay 275 of repeater F' is as follows: from ground through line relay 275, resting contact of armature 175 and said armature, control conductor 164, lower winding 162 of impedance coil I¹, resting contact of armature 127 and said armature, resting contact of armature 130 and said armature, trunk conductor 132, lower winding 135 of 90 impedance coil I, spring 170 of jack J' and its working contact, normally closed contacts controlled by spring 171 of key K², and resistance R⁸ to battery. 100

The operator throws key K², immediately 105 after inserting the plug into jack J² and thereby substitutes the calling device S' together with the resistance R for resistance R⁸.

The operator may now operate the calling device S' in accordance with the digit 110 3 which is the number of the substation Q, Fig. 4, and when she does so three momentary interruptions are produced in the circuit of the line relay 275 of repeater F' said 115 relay repeating them to the line relay 285 of the selector D². Line relay 285 is accordingly deenergized three times momentarily with the result that the selector D² operates to step the wipers 288, 289 and 290 120 up to the third level of bank contacts and then rotates them in search of an idle trunk line. The operation of switch D² is similar to the operations of switch D' and consequently need not be explained in detail except as regards the giving of the busy signal. The digit 3 gives access to the substation Q and since a person desiring connection with substation Q wishes to be connected with only that particular substation 125 130

and no other there is only one trunk line in the third level of D^2 , all the test contacts in the third level except the test contact 292 being grounded.

- 8 It will first be assumed that the trunk line on which the substation Q is located is busy when the call is made as above explained. In that case there is a ground potential on test contact 292 and accordingly
- 10 when the test wiper 289 reaches test contact 292 the wipers do not stop but continue to advance step by step until they pass off the last contact in that level and when they do so the cam 238 secured to the switch shaft
- 15 operates the springs 239 and 274. The operation of spring 274 opens the circuit of switching relay 287, while the operation of spring 239 connects the grounded busy lead 237 from the busy machine B, Fig. 2, to the
- 20 lower winding of line relay 285 and removes direct ground therefrom. This latter operation serves to give the operator a busy signal to inform her that the line is inaccessible for the time being and she, upon hearing it
- 25 operates key K' and thereby releases the connection.

It will now be assumed that the trunk line terminating in contacts 291-293, inclusive, is idle when the call is attempted

- 30 as previously explained, this being the case the arrival of test wiper 289 on test contact 292 is followed by the energization of switching relay 287 and the connection is extended by way of the bank contacts 291 and 293,
- 35 trunk conductors 255 and 257, and the upper and lower left windings of the repeating coil T^4 to the upper and lower windings, respectively, of line relay 376 of relay group P. The line and release relays 376 and 377
- 40 immediately energize and the latter grounds the release trunk conductor 256 at armature 381. This ground is placed on the release trunk before the slow acting release relay 286 of the selector D^2 has time to release and
- 45 serves to hold the selector in its operated position. By means of this ground potential on test contact 292 and its multiples the switch G and the relay group P are rendered busy to others. At the same time that the
- 50 release relay 377 grounds the release trunk as before explained it extends the connection to the called substation at armatures 382 and 383 by way of armature 384 and normally closed contacts operated by armature 385, and conductors 386 and 387. Battery from impedance 375 immediately flows over the connection to substation Q and thence by way of springs 389 and 390 of key K^3 and their resting contacts, trunk
- 55 conductors 394 and 395, left hand windings of repeating coil T^3 , armature 440 and its resting contact, armature 435 and its resting contact, and the upper winding of line relay 407 to ground. Relay 407 energizes and at
- 60 armature 434 closes the following circuit:

from ground through armature 441 and its resting contact, armature 434 and its working contact, armature 427 and its resting contact, and release relay 402 to battery. Release relay 402, upon energizing, connects 70 ground to release trunk conductor 450 at armature 418. This ground extends by way of the release trunk conductor 450 to the test contacts in the banks of all the switches having access to the selector repeater G' and 75 thereby protects the trunk line from intrusion at this end.

The connection has now been extended to the called substation but the bell thereat has not been rung. In order to ring the 80 bell at substation Q the operator operates the calling device S' for the digit 0, for example. In response to the impulses repeated to it, line relay 376 of relay group P deenergizes a plurality of times thereby 85 operating slow relay 378 through the resting contact of armature 379. Relay 378 energizes and retains its armatures attracted throughout the series of impulses and at its armatures 384 and 385 divides the trunk 90 into two sections and projects ringing currents from generator Gen. out on the section on which substation Q is located thereby 95 ringing the bridged bell thereat. It is easily seen that when the trunk is divided by the energization of relay 378 that battery from impedance 375 can no longer flow over the distant end of the trunk to keep the switch associated therewith busy. In order that battery be not removed from the distant end 100 of the trunk, battery is placed thereon by way of resistance R^7 and armature 385 and its working contact before the trunk is completely divided thereby maintaining the line and release relays of the switch G energized 105 so that the latter will not remove ground from the associated release trunk. At the end of the series of impulses the slow relay 378 deenergizes and obviously removes ringing current from the trunk line and unites 110 the two sections thereof. The operator may repeat the operation as many times as necessary in order to attract the attention of the subscriber at the called substation. When the subscriber at substation Q answers he 115 throws the key K^3 in the proper direction to operate the springs 392 and 393 and raises the receiver from the hook.

The talking circuit is now completed to the two substations and extends in either 120 direction from the paired repeaters F and F', Fig. 3, which are coupled together through talking condensers, as shown, the transmitter at the called substation being supplied with current from the local battery through the primary of the induction coil shown clearly in the drawing. The receiver is included in a bridge extending 125 across the trunk as follows: from conductor 386 by way of spring 389 and its resting con- 130

tact, spring 392 and its working contact, upper or secondary winding of induction coil 397, right working contact of the switchhook and said switchhook and its left working contact, the receiver, working contact of spring 393 and said spring, and the resting contact of spring 390 and said spring to conductor 387.

The required connection having been established, the subscribers may now converse as desired. When the conversation is finished both subscribers will hang up their receivers and the subscriber at substation Q also restores the key K³. When the receiver is replaced at substation A the circuit of back bridge relay 67 is broken and when it deenergizes, relay 67 reverses the conductors 258 and 260 as regards their connection with the windings of the line relay 66. This reverses the direction of current flow in conductors 258 and 260 and in the bridge across conductors 225 and 226 in repeater F to normal. The two windings of relay 202 now oppose each other; the said relay retracts its armature, and the circuit of relay 203 is broken. Relay 203, upon deenergizing, opens the bridge across conductors 225 and 226, disconnects the control circuit from battery through relay 205 at armature 212 and restores it to ground through line relay 204. Line relay 204 and the operator's supervisory relay 139 immediately energize in series over the operating circuit. The line relay 204, upon energizing, closes the bridge across the trunk conductors 225 and 226 before the connector H has time to release, and closes the circuit of release relay 200 again before it has time to deenergize. Supervisory relay 139 operates armature 142 and thereby lights the supervisory lamp 147.

When the operator perceives the disconnect signal she pulls down the connection. When the plug is removed from the jack J spring 145 disconnects the control circuit from supervisory relay 139 and battery and connects it to impedance 159 and thence to ground, this being the normal condition of the circuit. Supervisory relay 139 upon deenergizing, extinguishes lamp 147. Line relay 204 of repeater F, being no longer supplied with battery, deenergizes and at armature 216 opens the circuit of release relay 200, and at armature 217 opens the bridge across conductors 225 and 226 thereby releasing the connection to substation A in the well known manner. Upon deenergizing, release relay 200 opens the circuit of the polarizing winding of relay 202 at armature 208 and at armature 209 removes ground from the resting contact of armature 282 so that when the latter armature falls back ground will be removed from release trunk conductor 107.

66 When the plug is pulled from the jack J²

spring 170 disconnects the associated control circuit from battery through resistance R⁶ and connects it to ground through spring 146 and its resting contact and impedance 160. When battery is removed from the control circuit, as above explained, line relay 275 of repeater F' deenergizes and releases the connection to substation Q in the same manner as the deenergization of the line relay of repeater F releases the connections to substation A.

It will now be assumed that the subscriber at substation Q desires to obtain connection with the subscriber at substation A' whose number when called by a subscriber in the same C. A. X. is 345. When the subscriber at substation Q removes his receiver to make a call he also throws key K³ in such a direction that the springs 392 and 393 are operated. This allows him to listen in on the toll line and ascertain if it is in use or not. Assuming that the toll line is found to be idle, he throws the key to the opposite or calling position and when he does so the springs 388-391, inclusive, are operated. Springs 389 and 390 disconnect the section of the toll line comprising conductors 386 and 387 from the section comprising conductors 394 and 395 and connects it to a bridge that includes the upper or secondary winding of the induction coil 397 in series with the receiver. The spring 391 connects battery through resistance R' to conductor 395 to operate the line relay 407 of selector repeater G' which in turn operates the release relay 402 and thereby grounds the release trunk 450 to make switch G' test busy. Spring 388 connects battery through resistance R' and calling device S² by way of the switchhook springs, the bell coils in parallel, conductors 386 and 387, armature 384 and its resting contact and the normally closed contacts controlled by armature 385, armatures 382 and 383 and their resting contacts, conductors 368 and 369, right hand windings of repeating coil T², armature 365 and its resting contact, armature 360 and its resting contact, and the upper winding of line relay 332 to ground. Line relay 332 immediately energizes and closes the following circuit for release relay 327: from ground by way of armature 366 and its resting contact, armature 359 and its working contact, armature 354 and its resting contact, and release relay 327 to battery. Release relay 327, upon energizing, opens at armature 347 a point in the circuit of release magnet 339 and prepares the circuit of vertical magnet 341 and grounds the release trunk conductor 253 at armature 346 in order to make switch G and also relay group P busy. When the ground is placed on release trunk conductor 253 the circuit of the upper or polarizing winding of electro polarized relay 333 is

closed. This winding alone, consisting of few turns of high resistance, is not able to operate the relay.

- The switch G is now ready for operation.
- 5 When the calling subscriber operates the calling device S^2 in accordance with the digit 0, or the number of the toll recording operator, the circuit of line relay 332 is interrupted ten times. In response to the 10 interruptions thus produced the line relay 332 is deenergized ten times momentarily and at each deenergization sends an impulse of current to the vertical magnet 341 over the following circuit: from ground through 15 armature 366 and its resting contact, armature 359 and its resting contact, armature 347 and its working contact, armature 350 and its resting contact, slow acting series relay 326, and vertical magnet 341 to battery. By the operation of the vertical magnet 20 net the switch shaft and wipers are raised step by step until the wipers 336, 337 and 338 stand opposite the tenth level of bank contacts. The slow acting relay 326 energizes in series with the vertical magnet 25 and retains its armature attracted throughout the vertical movement and upon the closure of off normal contacts 301 completes the circuit of the stepping relay 325. Upon 30 energizing, relay 325 prepares the circuit of rotary magnet 340 at armature 343 and at armature 342 prepares a locking circuit for itself in series with interrupter springs 304. At the end of the vertical movement of the 35 shaft the slow acting relay 326 deenergizes and completes the circuit of the rotary magnet 340 which thereupon energizes to advance the wipers 336-338, inclusive, into engagement with the first set of bank contacts in the level opposite which they are 40 raised. The rotary magnet also breaks the circuit of stepping relay 325. The said relay deenergizes and opens the circuit of the rotary magnet, which thereupon deenergizes 45 also and again closes its interrupter contacts. The operation now depends upon whether the first trunk is busy or idle. If the first trunk is busy there is a ground potential upon the test contact with which 50 test wiper 337 is in engagement and the stepping relay is energized again and the same cycle of operations is repeated over and over until an idle or ungrounded test contact is reached. When an idle set of 55 contacts is reached the switching relay 328 energizes in series with the stepping relay over the following circuit: from grounded release trunk 253 through switching relay 328, interrupter contacts 304, off normal 60 springs 301, and stepping relay 325 to battery. Relay 325, however, due to its relatively small number of turns does not energize over this circuit. It is assumed that the test contact 306 is the first one found idle. 65 In this case the energization of switching

relay 328 completes the following circuit: from ground by way of grounded release trunk conductor 253, working contact of armature 349 and said armature, test wiper 337, test contact 306, release trunk conductor 70 107, armature 282 of release relay 276 of repeater F' and its resting contact, armature 209 of relay 200 and its resting contact, conductor 109, armature 126 and its resting contact, and slow acting relay 122 to battery. Relay 122 energizes and closes the circuit of relay 123 which energizes and projects generator out over the trunk line 131-132 to operate drop 143. This all happens in the same manner as described in the 80 previous case in which the subscriber at substation A called the operator.

Returning now to the selector repeater the energization of switching relay 328 closes the following bridge across line wipers 336 85 and 338: from line wiper 338 by way of armature 352 and its working contact, lower left winding of repeating coil T^2 , armature 351 and its working contact, lower winding of electro-polarized relay 333, resistance R^3 , 90 working contact of armature 345 and said armature, upper left winding of repeating coil T^2 , working contact of armature 308 and said armature, the armature of release magnet 339 and its resting contact, and line 95 wiper 336. Over this bridge the line relay 120 of relay group E energizes and operates the release relay 121 thereby opening the circuit of relay 122 which falls back and opens the circuit of relay 123. Relay 123 falls 100 back later and removes generator from the trunk line. The electropolarized relay 333 included in the bridge across line wipers 336 and 338 does not energize at this time because the current in its lower winding 105 opposes that flowing in its upper winding.

The operator upon observing the operated condition of drop 143 restores it to normal and inserts a plug of an idle cord circuit into jack J and associates her head set with the 110 cord circuit. After finding out who is calling and who he desires to be connected with, she tells him to hang up his receiver. He does so and also returns key K^3 to normal, thereby releasing the connection and restoring the conditions on the associated trunk line to normal.

The release of switch G will now be described in detail. When the receiver is replaced at substation Q the circuit of line relay 332 of switch G is broken and the said relay accordingly deenergizes. At armature 359 line relay 332, upon falling back opens the circuit of release relay 327. Release relay 327, upon deenergizing, removes ground 120 from release trunk conductor 253 at armature 346, and at armature 347 closes the following circuit for release magnet 339: from ground by way of armature 366 and its resting contact, armature 359 and its resting con- 125 130

- tact, armature 347 and its resting contact, off normal contacts 302, and release magnet 339 to battery. The release magnet upon energizing restores the switch shaft and wipers to normal, its circuit being opened at off normal contacts 302 by the shaft when the latter reaches normal position.
- When the connection is released as described the line and release relays 120 and 121 of relay group E deenergize and the latter restores the operator's control circuits to normal at armatures 125 and 127. The supervisory relay 139 immediately energizes in series with line relay 204 of repeater F over a previously traced circuit and attracts its armature 142 thereby lighting supervisory lamp 147. The operator upon seeing the lighted condition of lamp 147 knows that the subscriber at substation Q has hung up his receiver and that she may now proceed with the call.
- To do this the operator removes the plug from jack J and inserts it into jack J^2 and proceeds to call the subscriber at substation Q as she did in the previous example. We shall assume that she obtains connection with relay group P and that she operates her calling device in the usual manner to ring the bridged bell at substation Q.
- When the subscriber at substation Q answers, in response to the ringing of the bell thereat, he not only removes his receiver but also throws key K^3 in such a manner as to operate springs 392 and 393 thus completing the talking circuit. After ascertaining that he is the person desiring the connection with the subscriber at substation A', the operator requests him to remain on the line while she calls the desired subscriber.
- The operator now removes the plug from jack J^2 thereby releasing the established connection. She then inserts a plug into jack J and when she does so supervisory relay 139 and line relay 204 of repeater F energize in series over the control circuit in the usual manner. Line relay 204 closes the circuit of release relay 200 and also closes the usual bridge across conductors 225 and 226, thereby making the selector D' ready for the usual impulses. Release relay 200 of the repeater F energizes and prepares the repeater for repeating properly the usual impulses. The operator now throws the proper key and thereby includes the calling device in the control circuit. She now operates her calling device in accordance with the digit 2 which is the digit that gives access to the C. A. X. in which substation A' is located, and when she does so the selector D' steps its wipers up to the second level of bank contacts and rotates them in search of an idle trunk line. We shall assume that the trunk line terminating in contacts 246-248, inclusive, is idle and consequently is selected since it is the only trunk line terminating in that level. That being the case the operation of switching relay 221 switches the connection through to the trunk line terminating in bank contacts 246, 247 and 248. A ground potential by way of armature 226 of release relay 228 and armature 234 of switching relay 221 is immediately sent forward to ground test contact 247 and its multiples in order to make the selected trunk busy immediately. This ground potential, in addition to making the selected trunk busy, extends by way of jumper 300, release trunk conductor 256, armature 381 of relay group P and its resting contact, and release trunk conductor 253 to battery 70 through the upper winding of electro-polarized relay 333. The upper winding of electro-polarized relay 333 is such that it cannot operate the relay until it is assisted by current in the lower winding as has been 80 explained before. The ground potential extends still further by way of armature 346 and its resting contact, off normal contacts 303, armature 362 and its resting contact, resting contact of armature 353 and said armature, to battery through reversing relay 330. Reversing relay 330 is wound with a large number of turns and is given a stiff adjustment, the two features combining to make it slow to pull up, and consequently it 90 does not operate immediately. A further result of the operation of switching relay 221 of switch D' is that it extends the connection by way of armatures 233 and 236 and their working contacts, wipers 240 and 242, bank contacts 246 and 248, trunk conductors 252 and 254, upper and lower left windings of repeating coil T^2 , armatures 345 and 351 and their resting contacts, and normally closed contacts of reversing relay 100 330 to the upper and lower windings of line relay 331. The line relay 331 immediately energizes and operates release relay 335, at armature 358. Release relay 335, upon energizing, places ground on release trunk conductor 253 by way of armature 366 and its working contact, off normal contact 303, and resting contact of armature 346 and said armature. This ground extends back by way 110 of the resting contact of armature 381 and 115 said armature, release trunk conductor 256, and jumper 300 to test contact 247 to maintain the switch D' in its operated position. Further results of the energization of release relay 335 are that the circuit of slow 120 relay 334 is prepared at armature 367 and the trunk control circuit is switched from its normal path to ground through the upper winding of relay 332 to battery by way 125 of armature 365 and its working contact, lower winding of relay 329, working contact of armature 357 and said armature, and resistance R^2 . Relay 329 of switch G and line relay 407 of switch G' immediately energize in series over the following circuit: 130

from ground by way of line relay 407 of switch G', resting contact of armature 435 and said armature, resting contact of armature 440 and said armature, upper and lower 5 left windings of repeating coil T³, trunk conductors 394 and 395, resting contacts of springs 389 and 390 of key K³ and said springs, trunk conductors 386 and 387 armature 384 and its resting contact and normally closed contacts controlled by armature 385, armatures 382 and 383 and their resting contacts, conductors 368 and 369, upper and lower right windings of repeating coil T² and thence by way of previously traced circuit to battery. Since the circuits of switches G and G' are identical the energization of the line relay 407 of G' is effective to energize the release relay 402 and thus make the switch busy and prepare it 10 for the operating impulses in the same manner as the line and release relays 332 and 327 prepared switch G for operation when the subscriber at substation Q made the call previously described.

25 In the switch G the only effect produced at this time by the energization of relay 329 is the opening of the circuit of reversing relay 330, at armature 353. This occurs before the slow to pull up reversing relay has 30 had time to energize.

The operator may now operate her calling device for the second digit 3 of the desired number. The repeater F repeats these impulses to the line relay 331 of switch G.

35 The line relay 331 is accordingly deenergized three times momentarily and at armature 357 opens the circuit of line relay 407 of switch G' three times momentarily. The effect of this operation will be described later.

40 Each time line relay 331 deenergizes it not only opens the controlling circuit at armature 357 as explained but also closes the circuit of slow relay 334 at armature 358. Relay 334 operates and maintains its armatures attracted during the entire series of impulses. At armature 363 relay 334 closes a shunt around the lower winding of relay 329 so as to obtain a better impulsive circuit for line relay 407 of switch G', while at armature 362 it opens a point in the circuit of reversing relay 330 to prevent its operation at this time due to the deenergization of relay 329 when the shunt is placed around its lower winding. When the impulses 50 cease slow relay 334 falls back, removes the shunt from the lower winding of relay 329, and at the same time closes the circuit of reversing relay 330 at armature 362. Reversing relay 330 being slow to energize does not have sufficient time to operate before relay 329 operates and opens its circuit at armature 353.

The operation of the selector repeater G' on the distant end of the toll line will now 55 be described in detail. Each time the line relay 407 deenergizes due to the opening of its circuit by armature 357 of the switch G, armature 434 falls back and closes the following circuit: from ground by way of armature 441 and its resting contact, armature 434 and its resting contact, armature 419 and its working contact, armature 424 and its resting contact, slow acting series relay 401, and vertical magnet 412 to battery. By the operation of the vertical magnet 412 the switch shaft and wipers 443-445, inclusive, are raised step by step until the wipers stand opposite the desired level of bank contacts, which in this case is the third. Slow acting relay 401 operates and retains 70 its armature attracted throughout the vertical movement of the shaft and upon the closure of vertical off normal contacts 420 completes a circuit for stepping relay 400. Upon energizing, relay 400 prepares the circuit of the rotary magnet at armature 414 and establishes a locking circuit for itself at armature 413 in series with the contacts 449 controlled by the rotary magnet 411. At the end of the vertical movement of the shaft the slow acting relay 401 deenergizes and completes a circuit for the rotary magnet 411 which thereupon energizes to advance the wipers 443-445, inclusive, into engagement with the first set of contacts in 80 the level opposite which they are raised, at the same time opening the locking circuit of stepping relay 400 at its interrupter contacts. Stepping relay 400 accordingly deenergizes and breaks the circuit of the rotary magnet which thereupon deenergizes also and again closes its interrupter contacts. The operation now depends upon whether the test contact with which the test wiper 444 is in engagement is busy or idle. If the 85 test contact is busy there is a ground potential on it and the stepping relay energizes again and the same cycle of operation is repeated over and over until an idle or ungrounded test contact is reached. When an idle set of contacts is reached the switching relay 403 energizes in series with the stepping relay 400 over the following circuit: from ground by way of working contact of armature 418 of release relay 402 and said armature, switching relay 403, interrupter contact 449, off normal contacts 420, and stepping relay 400 to battery. Relay 400, however, due to its relatively small 90 number of turns and comparatively stiff adjustment does not energize over this circuit. It is assumed that test contact 447 is the first one found idle. In this case the energization of the switching relay 403 closes a bridge across the trunk line comprising conductors 473 and 475 terminating in the contacts 446 and 448. This bridge may be traced as follows: from line wiper 445 by way of armature 433 and its working contact, lower right winding of repeat- 95

ing coil T^3 , armature 425 and its working contact, lower winding of electro polarized relay 408, resistance R^6 , working contact of armature 417 and said armature, upper right winding of repeating coil T^3 , armature 432 and its working contact, and the resting contact of the armature of release magnet 415 and said armature to line wiper 443. The closure of this bridge results in the operation of line relay 476 of connector H' , for the conductors 473 and 475 terminate in the upper and lower windings of said relay, passing by way of normally closed reversing contacts of the back bridge relay 479. The line and release relays of the connector H' energize in the usual manner thus preparing the connector for the usual impulses. Since connector H' is identical with the connector H and the operation of the latter has already been described it is not thought necessary to describe the operation of the connector H' in detail. It will suffice to say that connector H' operates in accordance with the last two digits 4 and 5 to give access to the line of substation A' and that when the subscriber thereat responds to the ringing of his bell by removing his receiver he causes the usual operations to take place in the connector, which results in the energization of back bridge relay 479 and the consequent reversal of the connection of conductors 473 and 475 as regards the windings of line relay 476. The reversal of the conductors 473 and 475 results in the operation of the electro polarized relay 408 in the bridge thereof because its two windings now assist each other. When the elector polarized relay 408 operates it switches the control circuit from its normal path to ground through the upper winding of line relay 407, to battery by way of the upper winding of relay 404, and closes at armature 436 a locking circuit for the lower winding of line relay 407. The condition now existing is that the trunk line extending from switch G to switch G' is connected to the live pole of battery at each end and consequently there is no flow of current over it. As a result relay 329 in the selector repeater G deenergizes and at armature 353 closes the circuit of reversing relay 330. The reversing relay 330, upon energizing, reverses the direction of the current flow in the conductors 252 and 254 and consequently in the bridge across the conductors 225 and 226 at repeater F . Electro polarized relay 202 of the repeater F accordingly energizes and, in a manner before explained, connects the live pole of battery to control conductor 163, allowing the supervisory relay 139 to deenergize and extinguish supervisory lamp 147 in front of the operator to apprise her of the fact that the called subscriber has answered.

The called and calling subscribers may now converse with each other in an obvious manner and when the conversation is completed they will both hang up their receivers. The replacing of the receiver at substation A' reverses the flow of current in conductors 473 and 475 to normal. This causes the electropolarized relay 408 to deenergize and restore the control circuit to its normal path to ground by way of the upper winding of relay 407. This reoperates relay 329 of switch G . Relay 329, upon energizing, opens the circuit of reversing relay 330 at armature 353. Relay 330, upon deenergizing, reverses the current flow in the conductors 252 and 254 to normal whereupon the electropolarized relay 202 in the repeater F is deenergized. This results finally in the switching of control conductor 163 back to its normal path to ground by way of line relay 204. The supervisory relay 139 on the other end of the control circuit is again energized and lamp 147 is again lighted to apprise the operator of the fact that conversation is finished.

The operator upon noting the lighted condition of supervisory lamp 147 pulls down the connection. When the plug is removed from jack J the control circuit is restored to its normal path to ground through impedance 159. This results in the deenergization of supervisory relay 139 and also the line relay 204 of repeater F . As a result the supervisory lamp 147 is extinguished and the bridge across conductors 225 and 226 at repeater F is opened. This allows line relay 331 of the switch G to deenergize and open the circuit of release relay 335. When relay 335 deenergizes, the control circuit extending to switch G' is restored to its normal path to ground by way of the upper winding of line relay 332. This obviously results in the deenergization of line relay 407 of repeater G' and the consequent deenergization of release relay 402. When release relay 402 deenergizes the following circuit is completed: from ground by way of armature 441 and its resting contact, armature 434 and its resting contact, armature 419 and its resting contact, off normal contacts 421, and release magnet 415 to battery. Release magnet 415 energizes, and restores the switch shaft and wipers to normal position in the usual manner. The opening of the bridge across trunk conductors 473 and 475 obviously results in the usual release of connector H' and accordingly need not be explained.

It is seen that each of the two connections that have just been described includes the subscriber at substation Q either as a calling or called subscriber. As a matter of fact calls to and from the substation Q as compared to the total number of calls in the entire system will be very few indeed, the majority of the calls being between two

subscribers such as the subscriber at substation A and the subscriber at substation A'. In a call to substation Q it will be noted also that there is provided no way for giving supervision to the operator when the subscriber at substation Q answers or hangs up his receiver. Calls to substation Q are very rare and it is not thought necessary to make any special or elaborate provisions to overcome this difficulty.

A call will now be described that will be typical of practically all the calls that are to be made from one exchange to another. For this purpose it will be assumed that the subscriber at substation A' desires to obtain connection with the subscriber at substation A. In order for the subscriber at substation A' to obtain connection with the toll recording operator he must dial two digits. The first digit is 0 and gives connection to the C. A. X. that is nearer the operator. The second digit is also 0 and as explained before gives connection with the operator. When the subscriber at substation A' removes his receiver to initiate the call his line switch C' operates in a manner similar to that described for the line switch C to extend the calling line to an idle trunk line. We shall assume the trunk line leading to selector D³ is the one selected. This being the case, the line and release relays 461 and 462 in the selector D³ operate in the usual manner and perform the usual functions. In response to the digit 0 the selector D³ raises its wipers 464-466, inclusive, step by step until they stand opposite the tenth level of bank contacts. The wipers are then automatically rotated to pick out an idle trunk line in the level opposite which they are raised. It will be assumed that the trunk line terminating in the bank contacts 467, 468 and 471 is the first one found idle and consequently the one selected. This being the case the energization of switching relay 463 switches the connection through by way of trunk conductors 449 and 451, upper and lower right windings of repeater coil T³, armatures 417 and 425 and their resting contacts, normally closed contacts controlled by reversing relay 405 to the upper and lower windings of line relay 406. It will be appreciated that this operation is substantially the same as the operation described in which the selector D' was used to obtain connection to the switch G in a preceding example, the circuits of the two switches G and G' being identical. This being the case it is not thought necessary to describe the operation of switch G' in detail. However, it may be said that when the switch G' is seized that it immediately closes the proper circuits in order to prepare the switch G for receiving the usual impulses. When the calling device is again turned the switch G'

acts as a repeater and repeats the impulses received to the switch G in the distant exchange. In response to the impulses thus received the switch G raises its wipers 336, 337, 338 step by step until they stand opposite the tenth level of bank contacts and rotates them in search of an idle trunk line. It will be assumed that the trunk line terminating in bank contacts 305-307, inclusive, is the first one found idle and consequently the one selected. This being the case the energization of switching relay 328 extends the connection in the same manner as was described in the case in which the subscriber at substation Q called the operator. In response to the call thus received the operator will insert a plug into the jack J and ascertain from the calling subscriber his own number and the number with which he desires connection. After obtaining the desired information the operator requests the calling subscriber to hang up his receiver and when he does so the connection just described is released. The operator then operates her calling device in the usual manner and thereby reestablishes connection with him in order to ascertain whether or not he has given the correct number. When the subscriber at substation A' answers the final result is that supervisory lamp 147 in front of the operator is extinguished as before described. The operator upon seeing the lamp become extinguished knows that he has answered and takes the proper steps to converse with him and upon ascertaining that he is the person that desires the connection she instructs him to wait on the line while she calls the number he wants. She then inserts a plug into the jack J' and proceeds to call the subscriber at substation A. Since such a call has been described before it will suffice at this time to say that when the call is finally completed and the subscriber at substation A answers the consequent reversal of battery finally results in the supervisory lamp 148 becoming extinguished. The operator then listens to ascertain if the party who answered the telephone is the one wanted and assuming that he is the subscriber may now converse with each other. When the conversation is finished the subscribers will hang up their receivers and the release will take place in the usual manner. When the two connections are released both supervisory lamps 147 and 148 become lighted and the operator upon seeing this will pull down the connection. If, however, one subscriber hangs up and the other fails to do so only the particular lamp associated with the connection to the subscriber that has hung up will become lighted. However, this will not prevent the releasing of the connection for the operator upon removing the plugs from the jacks

causes the circuit conditions to be restored to normal. Assuming that it is the subscriber at substation A' that has not hung up the removal of the plug from jack J will cause the control circuit to be switched to its normal path to ground through impedance 159. The other end of the control circuit in repeater F is connected at this time to battery by way of relay 205 and the result is that relay 205 energizes and at armature 218 opens the circuit of release relay 200. When release relay 200 deenergizes it opens the upper or polarizing winding of electro polarized relay 202 at armature 208 with the result that relay 202 is deenergized for the lower winding alone cannot hold the relay operated. When relay 202 deenergizes it opens the circuit of relay 203. Relay 203 upon deenergizing, opens the bridge across the conductors 225 and 226 at armature 215. The opening of the bridge allows the line relay 331 and release relay 335 of selector repeater G to deenergize. Release relay 335 upon deenergizing removes ground from release trunk conductor 253 at armature 366 thereby allowing selector D' to restore to normal position, and at armature 365 restores the control circuit that extends to switch G' to its normal path to ground through the upper winding of line relay 332. Since the other end of the control circuit is connected to battery through the upper winding of relay 404 of switch G' the line relay 332 of switch G and relay 404 of switch G' energize in series with each other. In switch G the line relay 332, upon energizing, closes the circuit of release relay 327. Release relay 327 energizes and at armature 346 places ground on release trunk 253 thereby rendering the toll line busy for the time being. In switch G', relay 404 upon energizing opens the circuit of release relay 402 at armature 327 and upon the deenergization of release relay 402 completes the following circuit for release magnet 415: from ground by way of armature 441 and its resting contact, armature 434 and its working contact, armature 427 and its working contact, armature 419 and its resting contact, off normal contacts 421, and release magnet 415 to battery. By the operation of the release magnet 415 the switch shaft and wipers are restored to normal position, the circuit of release magnet 415 being broken at off normal springs 421. With the switch in normal position all the relays deenergize and the control circuit is restored to its normal path to ground through line relay 407. The line relay 332 of switch G also deenergizes and opens the circuit of release relay 327 which deenergizes and removes ground from the release trunk conductor 253 at armature 346. It is easily seen that since there is nothing now to hold the line relay 476 of connector H' en-

ergized that it must fall back and release must take place in the usual manner. All the equipment is now restored to common use.

In view of the foregoing it is obvious that the subscriber at substation A can obtain connection with the subscriber at substation A', and it may be stated also that the subscriber at substation A can by calling the proper number obtain connection with any other subscriber whose line terminates in the same C. A. X. without first obtaining connection with the operator, for in making such calls there is no charge. The same is true for the subscribers in the other C. A. X. The subscriber at substation Q, however, can make no call whatsoever except through the operator at the large automatic exchange.

After a careful study of the system it becomes apparent that some arrangement must be made in order for the subscribers at either of the C. A. X.'s or the subscriber at substation Q to obtain connection with the subscribers in the large automatic exchange. This is taken care of by providing outgoing trunks extending from the operator's position to automatic switches through the medium of which the operator can extend a connection to any subscriber whose line terminates in the exchange in which she is located. There may be other toll lines also from other exchanges, either automatic or manual, terminating in front of the same operator. It is easily seen that the operator can extend a call from any one of these toll lines to any other by means of her cord circuits in the usual manner. Likewise a call from any one of these toll lines or from the large automatic exchange, can be extended to any subscriber whose line terminates in either C. A. X. or to the subscriber at substation Q. These connections, however, involve the use of apparatus whose operation has already been fully described, and consequently they need not be considered in detail.

Having described our invention, what we consider to be new and desire to secure by Letters Patent will be pointed out in the appended claims.

What we claim as our invention is:

1. In a telephone system, two exchanges and an interconnecting toll line comprising only two conductors, branches of said toll line at one exchange, automatic switches for extending said branches separately into connection with subscribers' lines, a manual switch board at the other exchange, and means whereby the operator can control said switches to establish a three way talking circuit including herself and two subscribers in the distant exchange.

2. In a telephone system, a trunk line extending from an operator's position in one

- exchange to a second exchange, two branches of said trunk line at the second exchange, automatic switches controlled by the operator in the first exchange for extending said branches to subscribers' lines to connect with two lines at the same time, and two supervisory signals at said position controlled by the two connected subscribers, respectively.
3. In a telephone system, a first exchange, a second exchange, a toll line connecting said exchanges, branches of said toll line at the second exchange, automatic switches for extending said branches separately into connection with subscribers' lines, a manual switchboard at the first exchange, means whereby the operator can control said switches, two supervisory signals at said switchboard, and means whereby each connected subscriber can control a particular one of said signals when he answers and hangs up his receiver.
4. In a telephone system, a first exchange, a second exchange, a toll line connecting said exchanges, branches of said toll line at the second exchange, automatic switches for extending said branches separately into connection with subscribers' lines, a manual switchboard at the first exchange, two independent control circuits each including a talking conductor of said toll line, and means whereby the operator can control over one of said circuits the switches for extending one of said branches and over the other of said circuits the switches for extending the other branch.
5. In a telephone system, a first exchange, a second exchange, a toll line connecting said exchanges, branches of said toll line at the second exchange, automatic switches for extending said branches separately into connection with subscribers' lines, a manual switchboard at the first exchange, two independent control circuits each including a talking conductor of said toll line, means whereby the operator can control over one of said circuits the switches for extending one of said branches and over the other of said circuits the switches for extending the other branch, two supervisory signals at said switchboard, means whereby one of the connected subscribers can control one of said signals over one of said control circuits, and means whereby the other connected subscriber can control the other of said signals over the other control circuit.
6. In a telephone system, first, second, and third exchanges, a toll line connecting the first and second exchanges, another toll line connecting the second and third exchanges, a manual switchboard at the first exchange, two branches of said first toll line at the second exchange, automatic switching mechanism controlled by an operator at said switchboard for extending one of said branches into connection with a subscriber's line in the second exchange, other automatic switching mechanism controlled by said operator for extending the second branch into connection with said second toll line, and still other automatic switching mechanism controlled by said operator for extending the second toll line into connection with a subscriber's line in the third exchange.
7. In a telephone system, first, second, and third exchanges, a toll line connecting the first and second exchanges and having an extension in the second exchange, a second toll line connecting the second and third exchanges, a trunk line in the third exchange, automatic switching mechanism for connecting the said extension with the said second toll line, automatic switching mechanism for connecting the second toll line with said trunk line, automatic switching mechanism for connecting said trunk line with a subscriber's line, a switch control circuit including a single conductor of said first toll line, a second switch control circuit including the two sides of said extension in series, a third switch control circuit including the two conductors of said second toll line in parallel, and a fourth switch control circuit including the two conductors of said trunk line in series.
8. In a telephone system, first, second, and third exchanges, a toll line connecting the first and second exchanges and having an extension in the second exchange, a second toll line connecting the second and third exchanges, a trunk line in the third exchange, automatic switching mechanism for connecting the said extension with the said second toll line, automatic switching mechanism for connecting the second toll line with the said trunk line, automatic switching mechanism for connecting said trunk line with a subscriber's line, a switch control circuit including a single conductor of said first toll line, a second switch control circuit including the two sides of said extension in series, a third switch control circuit including the two conductors of said second toll line in parallel, a fourth switch control circuit including the two conductors of said trunk line in series, means for generating switch operating impulses in the first control circuit, and means for repeating impulses from each control circuit into the next, whereby a line in the first exchange may be connected with the said subscriber's line in the third exchange.
9. In a telephone system, first, second, and third exchanges, a toll line connecting the first and second exchanges and having an extension in the second exchange, a second toll line connecting the second and third exchanges, a trunk line in the third exchange, automatic switching mechanism for connect-

- ing the said extension with the said second toll line, automatic switching mechanism for connecting the second toll line with the said trunk line, automatic switching mechanism for connecting said trunk line with a subscriber's line, a switch control circuit including a single conductor of said first toll line, a second switch control circuit including the two sides of said extension in series, a third switch control circuit including the two conductors of said second toll line in parallel, a fourth switch control circuit including the two conductors of said trunk line in series, means for generating switch operating impulses in the first control circuit, means for repeating impulses from each control circuit into the next, whereby a line in the first exchange may be connected with the said subscriber's line in the third exchange, and circuit arrangements whereby current flow over the said first and third control circuits is prevented during conversation.
10. In a telephone system, first, second, and third exchanges, a toll line connecting the first and second exchanges, another toll line connecting the second and third exchanges, a manual switchboard at the first exchange, two branches of said first toll line at the second exchange, automatic switching mechanism controlled by an operator at said switchboard for extending one of said branches into connection with a subscriber's line in the second exchange, other automatic switching mechanism controlled by said operator for extending the second branch into connection with said second toll line, still other automatic switching mechanism controlled by said operator for extending the second toll line into connection with a subscriber's line in the third exchange, a switch control circuit associated with one of said branches and including one conductor of said first toll line, a switch control circuit associated with the other of said branches including the other conductor of said first toll line, and a switch control circuit associated with the said second toll line including the two conductors thereof in parallel.
15. In a telephone system, first, second, and third exchanges, a toll line connecting the first and second exchanges, another toll line connecting the second and third exchanges, a manual switchboard at the first exchange, two branches of said first toll line at the second exchange, automatic switching mechanism controlled by an operator at said switchboard for extending one of said branches into connection with a subscriber's line in the second exchange, other automatic switching mechanism controlled by said operator for extending the second toll line into connection with a subscriber's line in the third exchange, and circuit arrangements whereby current flow over the said first and third control circuits is prevented during conversation.
20. In a telephone system, first, second, and third exchanges, a toll line connecting the first and second exchanges, another toll line connecting the second and third exchanges, a manual switchboard at the first exchange, two branches of said first toll line at the second exchange, automatic switching mechanism controlled by an operator at said switchboard for extending one of said branches into connection with a subscriber's line in the second exchange, other automatic switching mechanism controlled by said operator for extending the second toll line into connection with a subscriber's line in the third exchange, two supervisory signals at said switchboard controlled respectively by the connected subscribers in the second and third exchanges when they answer and replace their receivers.
25. In a telephone system, first, second, and third exchanges, a toll line connecting the first and second exchanges, another toll line connecting the second and third exchanges, a manual switchboard at the first exchange, two branches of said first toll line at the second exchange, automatic switching mechanism controlled by an operator at said switchboard for extending one of said branches into connection with a subscriber's line in the second exchange, other automatic switching mechanism controlled by said operator for extending the second toll line into connection with a subscriber's line in the third exchange, two supervisory signals at said switchboard, and means whereby the connected subscribers in the second and third exchanges can control said signals over the said switch control circuits after the connections are established.
30. In a telephone system, a first exchange and a second exchange, a trunk line connecting said exchanges, a station on said trunk line intermediate said exchanges, two branches of said trunk line at the first exchange one branch being for use when it is desired to call the second exchange while the other branch is for use in calling said station, automatic switches having access to both branches, and ringing equipment in the second of said branches for signalling said station.
35. In a telephone system, a first exchange and a second exchange, a two way trunk line connecting said exchanges, a station on said trunk line intermediate said exchanges, two branches of said trunk line at the first exchange one branch being for use in calling the second exchange while the other branch is for use in calling said station, automatic switches having access to both branches, other automatic switches having access to said trunk line in the second exchange, means for making said trunk line busy to all of said switches except the switch in use whenever the trunk line is called via the said second branch, and ringing equipment in the said second branch for signalling the said station.
40. In a telephone system, a first exchange and a second exchange, a two way trunk line connecting said exchanges, a station on said trunk line intermediate said exchanges, two branches of said trunk line at the first exchange one branch being for use in calling the second exchange while the other branch is for use in calling said station, automatic switches having access to both branches, other automatic switches having access to said trunk line in the second exchange, means for making said trunk line busy to all of said switches except the switch in use whenever the trunk line is called via the said second branch, and ringing equipment in the said second branch for signalling the said station.
45. In a telephone system, a first exchange and a second exchange, a trunk line connecting said exchanges, automatic switches in both exchanges, through the medium of which connections may be established over

- said trunk line in both directions, a station on said trunk line intermediate said exchanges, means at said station for operating one of said switches in the first exchange to extend a connection, and means in the second exchange controlled from said station over a talking conductor of said trunk line for making the line busy to the automatic switches in the second exchange. 65
- 10 16. In a telephone system, an operator's switchboard, a toll line, a supervisor lamp at said board, a station accessible by way of said toll line adapted to extinguish said lamp when the party thereat answers a call, another station accessible by way of said line incapable of extinguishing said lamp, a jack at said switchboard for use in extending calls over said toll line to the first station, a second jack at said switchboard for use in extending calls over said toll line to the second station, and circuit arrangements for lighting said lamp when connection is made with the first jack but not when connection is made with the second. 75
- 15 17. In a telephone system, a two way trunk line, two outgoing branches and one incoming branch at the same end of said trunk line, automatic switches in the banks of which said incoming branch terminates, a test conductor also multiplied in the banks 80 of said switches, means for signalling over said trunk line controlled over said conductor when the incoming branch is seized by one of said switches, and means for disconnecting the said conductor from said signalling means and for placing a busy potential on the said conductor whenever either one of said outgoing branches is in use. 85
- 20 18. In a telephone system, a trunk line having two branches at one end each terminating in an automatic switch, a line relay in one switch controlled solely over one conductor of said trunk line, and a line relay in the other switch controlled solely over the other conductor of said trunk line. 90
- 25 19. In a telephone system, a trunk line having two branches at one end each terminating in an automatic switch, a controlling circuit for setting one of said switches including one conductor of said trunk line and excluding the other, and a controlling circuit for the other of said switches including the second conductor and excluding the first. 95
- 30 20. In a telephone system, a trunk line having two branches at one end each terminating in an automatic switch, a controlling circuit for setting one of said switches including one conductor of said trunk line and excluding the other, a controlling circuit for the other of said switches including the second conductor and excluding the first, and circuit arrangements such that either controlling circuit can be used to set 100
- 35 its associated switch while the other switch is in use. 105
21. In a telephone system, a trunk line, two switch control circuits superimposed on said trunk line, two jacks either of which may be used for extending a connection to 70 said trunk line, means for closing one control circuit responsive to the insertion of a plug in one jack, and means for closing the other control circuit responsive to the insertion of a plug in the other jack. 75
22. In a telephone system, a trunk line, two switch control circuits superimposed on said trunk line, two jacks either of which may be used for extending a connection to 80 said trunk line, means for closing one control circuit responsive to the insertion of a plug in one jack, means for closing the other control circuit responsive to the insertion of a plug in the other jack, a calling device, and means for inserting said device in either 85 control circuit. 90
23. In a telephone system, a trunk line, a switch control circuit including a conductor of said trunk line, two jacks either of which may be used for connecting with said trunk 95 line, a supervisory relay, means responsive to the insertion of a plug in one jack for completing said control circuit over a path including said relay, and means responsive to the insertion of a plug in the other jack 95 for completing said control circuit over a path excluding said relay. 100
24. In a telephone system, lines, a pair of impulse controlled selective switches having a common talking path, leading-in talking 105 conductors for the said common path, automatic means for independently selectively operating the switches to connect the said common talking path with two said lines to form a Y talking connection between the said two lines and the said leading-in conductors, and automatic means for directly restoring and reoperating the respective switches independently regardless of control over said two connected lines. 110
25. In a telephone system, lines, a pair of impulse controlled selective switches having a common talking path, a leading-in trunk for the said switches, automatic means for independently selectively operating the 115 switches to connect the said common talking path with two said lines to form a Y talking connection between the said two lines and the said trunk, and means controlled over the trunk for applying signaling current independently to one or the other connected said line at will. 120
26. In a telephone system, called lines, a trunk line and terminating pair of automatic switches, means for independently operating 125 the switches over the trunk line to establish a Y talking connection between two said lines and the trunk line, and means con-

trolled over the trunk line to disconnect one or the other called line branch at will without destroying the remaining called line branch connection.

- 5 27. In a telephone system, called lines, a trunk line and terminating pair of automatic switches, means for independently operating the switches over the trunk line to establish a Y talking connection between two said lines and the trunk line, and means controlled over the trunk line to restore the switch linking one or the other called line branch at will without destroying the remaining called line branch connection.
- 10 28. In a telephone system, called lines, a trunk line and terminating pair of automatic switches, means for independently operating the switches over the trunk line to establish a Y talking connection between two said lines and the trunk line, and means controlled over the trunk line to restore and re-operate the switch linking one or the other called line branch at will without destroying the remaining called line branch connection.
- 15 29. In an automatic telephone system, a pair of automatic switches having a common talking path, called lines, an operating conductor for each said switch, means for operating the switches over the respective operating conductor to connect the called lines for talking service directly over the said common talking path, and means controlled over one or the other operating conductor for at will restoring and reoperating the corresponding switch.
- 30 30. In a telephone system, a pair of automatic switches having a common talking path, a pair of jacks one for each said switches respectively, called lines, an operator's circuit, supervisory mechanism, an impulse conductor for each switch and corresponding jack, means for independently operating the switches over the respective impulse conductor and jack from the operator's circuit to connect two called lines in talking relation over the said common talking path, means for effecting and effacing a responded condition of the respective called lines, and means including the supervisory mechanism and corresponding impulse conductor for indicating to the operator the said responded and said effaced state of the specific called lines.
- 35 31. In a telephone system, two exchanges and an interconnecting toll line comprising only two conductors, branches of said toll line at one exchange, automatic switches for extending said branches separately into connection with subscribers' lines, a manual switchboard at the other exchange, operator controlled means for operating said switches to establish a three way talking circuit including the operator and two subscribers in the distant exchange, and means controlled

by said operator for releasing said connection independent of any action on the part of said subscribers.

32. In a telephone system, two exchanges and an interconnecting toll line comprising only two conductors, branches of said toll line at one exchange, automatic switches for extending said branches separately into connection with subscribers' lines, a manual switchboard at the other exchange, operator controlled means for operating said switches to establish a three way talking circuit including the operator and two subscribers in the distant exchange, and means whereby the operator can release the connection extending over one of said branches to one of said subscribers without releasing the connection over the other branch to the other subscriber.

33. In a telephone system, a trunk line extending from an operator's position in one exchange to a second exchange, two branches of said trunk line at said second exchange, automatic switches controlled by the operator in the first exchange for extending said branches to subscribers' lines to connect with two lines at the same time, two supervisory signals at said position controlled by the two connected subscribers, respectively, and operator controlled means for at any time releasing said connection regardless of the unanswered, answered, or replaced positions of the receivers of said subscribers.

34. In a telephone system, a first exchange, a second exchange, a toll line connecting said exchanges, branches of said toll line at the second exchange, automatic switches for extending said branches separately into connection with subscribers' lines, a manual switchboard at the first exchange, operator controlled means for controlling said switches, two supervisory signals at said switchboard, means whereby each connected subscriber can control a particular one of said signals when he answers and hangs up his receiver, and operator controlled means for releasing said connection regardless of the answered or replaced condition of the receivers of said subscribers.

35. In a telephone system, first, second, and third exchanges, a toll line connecting the first and second exchanges, another toll line connecting the second and third exchanges, a manual switchboard at the first exchange, two branches of said first toll line at the second exchange, automatic switching mechanism controlled by an operator at said switchboard for extending one of said branches into connection with a subscriber's line in the second exchange, other automatic switching mechanism controlled by said operator for extending the second branch into connection with said second toll line, still other automatic switching mechanism con-

- trolled by said operator for extending the second toll line into connection with a subscriber's line in the third exchange, and operator controlled means for releasing said connections independent of control from said subscribers' lines.
36. In a telephone system, first, second, and third exchanges, a toll line connecting the first and second exchanges, another toll line connecting the second and third exchanges, a manual switchboard at the first exchange, two branches of said first toll line at the second exchange, automatic switching mechanism controlled by an operator at said switchboard for extending one of said branches into connection with a subscriber's line in the second exchange, other automatic switching mechanism controlled by said operator for extending the second branch into connection with said second toll line, still other automatic switching mechanism controlled by said operator for extending the second toll line into connection with a subscriber's line in the third exchange, and operator controlled means for releasing the connection over one of said branches to one of said subscribers' lines independent of control from such subscriber's line without interfering or releasing the connection to the other subscriber's line over the other branch.
37. In a telephone system, a first automatic exchange and a second automatic exchange, a trunk line connecting said exchanges, a station on said line intermediate said exchanges, said trunk lines having two branches at said first exchange, means for completing a connection from an automatic subscriber in the first exchange to said station via the first of said branches, means for completing a connection between said station and a subscriber in the second exchange via the second of said branches, ringing equipment in the second of said branches for signalling said station, and operator controlled means for releasing said connection independent of any act performed by said subscriber or said station.
38. In a telephone system, a first automatic exchange and a second automatic exchange, a trunk line connecting said exchanges, a station on said line intermediate said exchanges, said trunk lines having two branches at said first exchange, means for completing a connection from an automatic subscriber in the first exchange to said station via the first of said branches, means for completing a connection between said station and a subscriber in the second exchange via the second of said branches, the first of said branches terminating in a ringing repeater and the second of said branches terminating in a selector repeater, means for seizing said trunk line over the first branch when it is desired to signal said station, and means for seizing said trunk line over the second branch when it is desired to complete a connection between said station and a subscriber in said second exchange or when it is desired to complete a connection between a subscriber in the first exchange and a subscriber in the second exchange.
39. In a telephone system, a first automatic exchange and a second automatic exchange, a trunk line connecting said exchanges for use in completing connections between subscribers in said exchanges, a station on said line intermediate said exchanges, two branches of said trunk line at the first exchange, a third exchange; a trunk line connecting the first and third exchanges, an operator's position at said third exchange, said intermediate station unable to complete connections with subscribers' lines in either of said exchanges without the aid of the operator at said position, means including an automatic step by step switch in the first exchange directly controlled by said intermediate station over the first branch of said trunk line to complete a connection with said operator's position over the second of said trunk lines, and means including automatic switches in the first or second exchanges directly controlled by said operator for completing the connections between the intermediate station and the desired called subscribers' lines in either the first or second exchange.
40. In a telephone system, a first automatic exchange and a second automatic exchange, a trunk line connecting said exchanges for use in completing connections between subscribers in said exchanges, a station on said line intermediate said exchanges, two branches of said trunk line at the first exchange, a third exchange, a trunk line connecting the first and third exchanges, an operator's position at said third exchange, said intermediate station unable to complete connections with subscribers' lines in either of said exchanges without the aid of the operator at said position, means including an automatic step by step switch in the first exchange directly controlled by said intermediate station over the first branch of said trunk line to complete a connection with said operator's position over the second of said trunk lines, means including automatic switches in the first or second exchanges directly controlled by said operator for completing the connections between the intermediate station and the desired called subscribers' lines in either the first or second exchange, the connection between said intermediate station and a called subscriber in the first exchange including the second branch of said first trunk line, and the connection between said intermediate station

and a called subscriber in the second exchange being completed by way of the second branch of said first trunk line, and means at said position for controlling the 5 release of either of said connections independent of the other.

41. In a telephone system, a first automatic exchange and a second automatic exchange, a trunk line connecting said exchanges for use in completing connections between subscribers in said exchanges, a station on said line intermediate said exchanges, two branches of said trunk line at the first exchange, a third exchange, a trunk line connecting the first and third exchanges, an operator's position at said third exchange, said intermediate station unable to complete connections with subscribers' lines in either of said exchanges without the aid of the operator at said position, means including an automatic step by step switch in the first exchange directly controlled by said intermediate station over the first branch of said trunk line to complete a connection with said operator's position over the second of said trunk lines, means including automatic switches in the first or second exchanges directly controlled by said operator for completing the connections between the intermediate station and the desired called subscribers' lines in either the first or second exchange the connection between said intermediate station and a called subscriber in the first exchange including the second branch of said first trunk line, and the connection between said intermediate station and a called subscriber in the second exchange being completed by way of the second branch of said first trunk line, means 40 at said position for controlling the release of either of said connections independent of the other, and supervisory equipment at said position for informing the operator thereof of the answered or unanswered condition 45 and of the hanging up of the receivers by the connected subscribers.

42. In a telephone system, a first automatic exchange, a manual exchange, an operator's position at said manual exchange, a 50 trunk line connecting said exchanges and having two branches terminating in automatic switches in said automatic exchange, automatic switches in said automatic exchange controlled by calling subscribers therein for completing connections to local called subscribers' lines or to said operator's position over said trunk line, a second automatic exchange, a trunk line connecting said first and second automatic exchanges, automatic switches in the second automatic exchange controlled by calling subscribers therein to complete connections to local called subscribers' lines or to extend a connection over said trunk line to said first automatic exchange, an automatic switch in said 55

said first automatic exchange directly controlled over said second trunk line by calling subscribers in the second automatic exchange to complete a connection to said position over said first trunk line, the subscribers in each of said automatic exchanges 70 unable to control the automatic switches in the other of said automatic exchanges, and means controlled solely by the operator at said position for completing connections 75 between subscribers in the two automatic exchanges over said first and second trunk lines, the connection to the subscribers in the first automatic exchange including the first of said branches and the connection to the 80 subscribers in the second automatic exchange including the second of said branches.

43. In a telephone system, a first automatic exchange, a manual exchange, an operator's position at said manual exchange, a 85 trunk line connecting said exchanges and having two branches terminating in automatic switches in said automatic exchange, automatic switches in said automatic exchange controlled by calling subscribers 90 therein for completing connections to local called subscribers' lines or to said operator's position over said trunk line, a second automatic exchange, a trunk line connecting said first and second automatic exchanges, automatic switches in the second automatic exchange controlled by calling subscribers 95 therein to complete connections to local called subscribers' lines or to extend a connection over said trunk line to said first automatic exchange, an automatic switch in said 100 first automatic exchange directly controlled over said second trunk line by calling subscribers in the second automatic exchange to complete a connection to said position 105 over said first trunk line, the subscribers in each of said automatic exchanges unable to control the automatic switches in the other of said automatic exchanges to complete connections to called subscribers therein, means 110 controlled solely by the operator at said position for completing connections between subscribers in the two automatic exchanges over 115 said first and second trunk lines, the talking circuit between subscribers in the first and second automatic exchanges including said two branches, and operator controlled means at said position for supervising such established connections and for releasing and re-establishing such connections at the will of 120 the operator.

44. In a telephone system, two exchanges, a two conductor trunk line connecting said exchanges, two branches of said trunk line in the first exchange, automatic switches having access to said branches, means for operating one or more of said switches to seize 125 said trunk line over either of said branches, means responsive to a series of impulses after said trunk line has been seized over one 130

branch for connecting ringing current to the two conductors of said trunk line, and means responsive to a series of impulses after said trunk line has been seized over the 5 other of said branches for repeating a like number of impulses over a simplex circuit including the two conductors of said trunk line.

45. In a telephone system, two exchanges, 10 a two conductor trunk line connecting said exchanges, two branches of said trunk line terminating in said first exchange, means for seizing said trunk line over either one of said branches or at the second exchange, 15 means responsive to the seizure of said trunk line at either of its branches for making said branches busy and for making said trunk line busy at the second exchange over a simplex circuit including the two conductors of 20 said trunk line, means responsive to the seizure of said trunk line at said second exchange for making said branches busy over a simplex circuit including the two conductors of said trunk line, means for transmitting 25 impulses to either of said branches, means in said first branch responsive to such impulses in case the first branch is the branch seized for connecting ringing current to the two conductors of said trunk line, and means 30 in said second branch responsive to such impulses in case the second branch is the branch seized for repeating a like number of impulses over a simplex circuit including the two conductors of said trunk line.

35 46. In a telephone system, two exchanges, an impulse repeater, an operator's position including a cord circuit, a two conductor trunk line extending from said position in the first exchange and terminating in said 40 repeater in the second exchange, automatic switches in the second exchange, a ground return circuit including only one conductor of said trunk line and a line relay connected to ground in said repeater, operator controlled means including the plug of said cord circuit for sending impulses over said circuit to operate said line relay to repeat loop impulses to cause said switches to complete a connection with a called subscriber's line, a 45 guarding relay in said repeater controlled by said line relay, a third relay in said repeater connected to grounded battery, means in said repeater responsive to the called subscriber answering for disconnecting said line 50 relay and ground from said circuit, for connecting said third relay and grounded battery in place thereof, and for transferring the control of said guarding relay from said line relay to said third relay, and circuit 55 arrangements responsive to the operator at said position disconnecting the plug of her cord circuit from said trunk line for automatically grounding said circuit to energize said third relay to remove all control of said

guarding relay thereby permitting it to release and for automatically releasing said switches responsive thereto. 65

47. In a telephone system, two exchanges, an impulse repeater, an operator's position including a cord circuit, a two conductor 70 trunk line extending from said position in the first exchange and terminating in said repeater in the second exchange, automatic switches in the second exchange, a ground return circuit including only one conductor 75 of said trunk and a line relay connected to ground in said repeater, operator controlled means including the plug of said cord circuit for sending impulses over said circuit to operate said line relay to repeat loop impulses to cause said switches to complete a connection with a called subscriber's line, said line relay in energized position closing a bridge across the outgoing conductors of 80 said repeater for maintaining said switches operated, a second relay in said repeater connected to grounded battery, a third relay in said repeater operated responsive to the called subscriber answering, means controlled by said third relay for disconnecting 85 said line relay and ground from said circuit and for connecting said second relay and grounded battery to said circuit in place of said line relay, said means also closing an alternate bridge in place of the line relay bridge to maintain the switches operated, means responsive to the operator at said 90 position disconnecting the plug of her cord circuit from said trunk line for automatically grounding said circuit to energize said 100 second relay, and means controlled by the energization of said second relay for causing the deenergization of said third relay and the opening of the bridge across the outgoing conductors of said repeater to cause the release of said switches. 105

48. In a telephone system, two exchanges, an impulse repeater, an operator's position including a cord circuit, a two conductor trunk line extending from said position in the first exchange and terminating in said repeater in the second exchange, automatic switches in the second exchange, a ground return circuit including only one conductor of said trunk line and a line relay in said 110 repeater, operator controlled means including the plug of said cord circuit for sending impulses over said circuit to operate said line relay to repeat loop impulses to cause said switches to complete a connection with a called subscriber's line, a bridged holding circuit closed by said line relay in energized position to maintain said switches in operated position, means responsive to the called subscriber answering for causing 115 said line relay to deenergize and open a point in said bridged holding circuit and for closing another point in shunt of said opened 120 125

point for maintaining said bridged circuit and said automatic switches, and means controlled over said circuit responsive to the operator disconnecting her plug from said

5 trunk line for automatically opening said bridged holding circuit to cause the release of said operated switches.

Signed by me at Chicago, Illinois, this 10th day of February, 1921.

ARTHUR J. RAY.
